UNITED STATES PATENT OFFICE.

WILLIAM ALEXANDER AITKEN, OF GRAVESEND, ENGLAND.

PAPER-MAKING MACHINE.

1,264,254.

Specification of Letters Patent. Patented Apr. 30, 1918.

Application filed December 22, 1916. Serial No. 138,367.

To all whom it may concern:

Be it known that I, WILLIAM ALEXANDER AITKEN, a subject of the King of England, residing at Gravesend, in the county of Kent, in the Kingdom of England, have invented new and useful Improvements Relating to Paper-Making Machines, of which the following is a specification.

My invention relates to machines for making or treating pulp, paper-paste, card-board and the like and refers more particularly to an improved arrangement of heating and draining the drying cylinders of such machines in a simple and effective manner.

In existing machines of this kind, the wet pulp or paper-paste is taken in at the wet-end and passes over a plurality of drying cylinders until it reaches the dry-end of the machine in a practically dry condition, each cylinder having a different, *i. e.* superior temperature in sequence as the pulp passes from the one cylinder to the other toward the dry-end. Steam is used for heating the cylinders and is ordinarily let in at the wet-end. As the paper dries, the cylinders nearer the dry-end cannot condense so much steam as those at the wet-end, and consequently the steam, passing through the cylinders near the dry-end to the discharge pipe, prevents the uniform ejection of the condensation water from the cylinders of lower temperature at the wet-end of the machine. Some cylinders will keep full of water because a partial vacuum has been created in the low-temperature cylinders, or in the discharge pipe, and this may cause a blow-through of steam in the latter from the dry-end of the machine where condensation in the cylinders is not rapid. In this manner loss of steam and power occurs as a heavy load of undischarged water in various cylinders produces much friction on walls and bearings and greatly reduces the drying capability of said cylinders.

By my invention these drawbacks are avoided by the arrangement hereinafter described, which is so disposed as to keep the drying cylinders free from water; to utilize the steam which blows through from the dry-end cylinders; to obtain as much

heat as possible from the exhaust steam from the driving engines; to effect considerable economy in the consumption of live steam; and to reduce the pressure in all the drying cylinders.

The same or similar objects have previously been attained in a machine divided into sections with a first steam supply at the wet end of the machine which is complicated and expensive. It is my object to provide a machine of this type with a simple construction in which the outlet main from the dry-end section leads the steam direct into the inlet main for the wet-end cylinders.

In the following description reference is had to the annexed drawings, in which:—

Figure 1 is a side elevation of so much of a paper making machine as is necessary to illustrate my improved arrangement; Figs. 2 and 3 show in side view and plan respectively a detail of a modified part.

With my arrangement of mains I pass the exhaust steam from the driving engines and any live steam necessary to dry the pulp, paper-paste or the like, through a main inlet pipe 1 and induction pipe 2 into a group of cylinders A at the dry-end of the machine. From these cylinders the hot steam passes through eduction pipes 3 into the main outlet pipe 4 of the cylinders A. According to my invention the pipe 4 is directly connected to a separate steam supply pipe 5 for the cylinders B at the wet-end of the machine, said pipe 5 passing the steam through induction pipes 6 to the cylinders B whence it passes through eduction pipes 7 into a separate discharge pipe 8. It is advantageous to place the pipe 5 at a higher level than the pipe 4 so that water of condensation can drain into the water pocket 9 provided at the end of the main 4.

By following a previous arrangement and making a separate discharge pipe 8 for the low-temperature cylinders B, the steam blowing through from the dry-end is quickly taken up and consumed in the cylinders B owing to the rapid condensation which takes place in the latter. The water from these cylinders has a free passage to escape through the pocket 9 which acts here as an ejector under steam pressure. The rapid condensation of steam at the wet-end causes

a partial vacuum in the cylinders and this draws all the water from the cylinders at the dry-end.

The water pocket 9 discharges through pipe 10 with tap or valve 11 into the pipe 12 of a hot water receiver, said pipe 12 being connected with the discharge pipe 8. The tap 11 should be closed when paper making or the like is interrupted.

10 Instead of the discharge pipe 8 being connected with the eduction pipes 7 of the cylinders B, the said pipes 7 can be arranged as in Figs. 2 and 3, so as to individually discharge into an enlarged top 13 of the pipe 12 leading to the usual hot water receiver, and so insure for the perfect drainage of

condensation water from the cylinders B and other parts. More groups than two groups of drying cylinders can be adapted.

I claim:

25 In a paper making machine with cylinders divided into groups, the combination with the dry-end cylinders, of an inlet main and an outlet main at a level below that of the cylinders, a direct connection from the low level outlet main into a superposed inlet main for the wet-end cylinders, and a condensation discharge at the connecting end of said outlet main, as and for the purpose stated.

25 WILLIAM ALEXANDER AITKEN.
